UNITED STATES PATENT OFFICE

104,243

DESIGN FOR A COMBINATION DESK UNIT

Ray M. Chenoweth, Emmett M. Irwin, and Walter
P. Huntley, Los Angeles, Calif.

Application February 5, 1937, Serial No. 67,466

Term of patent 14 years

To all whom it may concern:

Be it known that we, Ray M. Chenoweth, Emmett M. Irwin, and Walter P. Huntley, citizens of the United States, said Ray M. Chenoweth residing in the city of Los Angeles, county of Los Angeles, State of California, and said Emmett M. Irwin and Walter P. Huntley both residing in the city of Pasadena, county of Los Angeles, State of California, have invented a new, original, and ornamental Design for a Combination Desk Unit, of which the following is a specification, reference being had to the accompanying drawing, forming part thereof.

The figure is a perspective view of a combination desk unit, showing our new design.

We claim:

The ornamental design for a combination desk unit, or similar article, as shown.

RAY M. CHENOWETH.
EMMETT M. IRWIN.
WALTER P. HUNTLEY.
